UNITED STATES PATENT OFFICE.

WILLIAM JOHN BONIFACE, OF SOUTHAMPTON, ENGLAND.

FILE CASE OR CABINET.

SPECIFICATION forming part of Letters Patent No. 562,352, dated June 16, 1896.

Application filed July 3, 1894. Serial No. 516,515. (No model.)

To all whom it may concern:

Be it known that I, WILLIAM JOHN BONIFACE, cabinet-manufacturer, a subject of the Queen of Great Britain, residing at 1st Anglesea Place, Southampton, in the county of Hants, England, have invented certain new and useful Improvements in File Cases or Cabinets; and I do hereby declare that the following is a full, clear, and exact description of the invention.

This invention relates to file cases or cabinets of the kind wherein a number of letter or other paper document files provided with suitable indexes are fitted in compartments in the case or cabinet.

The object of this invention is to construct file-cabinets of the kind above described in such manner that a cabinet for containing a given number of files shall occupy less floor or wall space and be arranged more conveniently for reference than a file-cabinet for containing the same number of files as heretofore constructed.

In use for filing ordinary papers the documents at the tail end of the file are approximately only one-half the thickness of the documents at the clip end. I take advantage of this fact to economize space in my file-cabinet.

In the accompanying drawings, which are furnished in illustration of my invention, Figures 1 and 2 are vertical sections, taken at right angles to each other, of a file-cabinet constructed in accordance with this invention and fitted in a pedestal outer case. Fig. 1^a is a detail of one of the files. Figs. 3 to 5 show details of construction, and Figs. 6 and 7 show modifications, all of which will be more fully explained hereinafter.

The same letters of reference where they occur in the several figures are used to indicate the same or corresponding parts.

In a suitable shell or outer case D, I journal a skeleton drum or cage A, made in the shape of a radial paddle-wheel or a segment thereof. This drum or cage I make sufficiently large to accommodate the files C which are placed therein, the compartments B between the successive radii or partitions b being made of such size that the files fit snugly thereinto and in such position that the documents filed lie in the plane containing the axis of the

drum or cage with the clip ends of the files at or near the circumference of the said drum or cage, as shown partially withdrawn from 55 the drum or cage in Fig. 1.

The file C consists of a simple board x, having at the end which is pointed toward the axle of the cage a projection y, to which is fastened at one end a spring z, the other end 60 pressing upon the board x. This spring therefore serves to keep down any papers which are inserted between it and the board. At the outer end of the board x, measured from the center of the cage, is a wire clip v, upon 65 which each paper is pressed and punctured by the said wire v, in the manner well known in the art.

To prevent the files falling out of the compartments B, I secure to the outer case or 70 shell D the arc-shaped boards E E in a position between the disks a a, forming the vertical walls or faces of the drum or cage A, (see Fig. 2,) or, on the outer edge of each partition b I may secure a spring device 75 such as is shown in Fig. 3, which consists of an ordinary spring b', secured to the underside of the partition and having a coiled or turned-up end b², which abuts against the outer edge c' of the base c of the file when the latter is in place. To withdraw the file, it is only necessary to turn the spring device down into the dotted position shown in Fig. 3, when the file can be withdrawn thereover. I may use this spring device in conjunction with the 80 arc-shaped boards E E if found convenient, or I may adopt any other device or arrangement which will effect the desired object.

In Fig. 1 the outer case or shell D completely incloses the rotatable drum or cage 90 A and is furnished with a lock-up door F, to which the files are successively brought by the rotation of the drum or cage. Secured to the axle of the drum or cage or to the drum itself when the latter rotates over a fixed 95 axis, and outside the case or shell D, is an indicator corresponding with the labels on the various files or when the latter are not labeled the indicator serves as an index to the files. When any given file is required, the 100 drum or cap is rotated by a handle or other suitable device until the index-symbol of the desired file is brought to a given position when the desired file is brought to the aper-

ture G in the outer case or shell D, formed by the open door F.

To stop the rotation of the drum or cage when the required file is brought to the door F, I prefer to adopt the arrangement shown in Fig. 4, which is an enlarged elevation of the outer case or shell D, showing the indicating device in position. Fig. 5 is a section taken on the line $x-x$ of Fig. 4. It will be seen that the indicating device consists, primarily, of a disk K, which is fixed by means of the distance-disks $d' d^2$ to the side a of the drum. The disk is metal-bound and rotates against the friction-rollers R, which are secured to the outer case or shell D. To the disk K is fixed a face-ring K^2 , divided into a number of equal parts corresponding with the number of compartments B in the drum or cage shown in Fig. 1. Each division of the face-ring K^2 has an index-symbol having reference to a given file and between every two succeeding divisions a locking-plate H is pivoted or hinged. One of these locking-plates is shown opened out on the left side of Fig. 5. The normal position of the locking-plate is at right angles to the ring K^2 , as shown most clearly at the bottom of Fig. 5. A plate J is attached to the casing D in front of which plate the member K revolves. At a suitable point in the casing D and the plate J a slot L is formed, into which any desired locking-plate can be turned on its pivot h^2 , thus locking the member K and the drum or cage with any desired file opposite the opening to permit withdrawal.

h^2 is the pivot of the plate H, and h^3 is a knob or finger-piece by means of which the said plate can be turned on its pivot and the disk K and consequently the drum or cage to which it is secured by means of the disks $d' d^2$ thereby rotated. In the outer ring J is the slot L above referred to, which slot is in line with the door F, and when the locking-plate H arrives at said slot the rib or projection h is pushed thereinto, thus stopping further rotation of the drum or cage A. This construction has been found very advantageous for the reason that in rotating the drum by means of the plates H the point h^4 can be pressed against the ring J and thus serving as a brake, prevents the too rapid rotation of the drum or cage, which otherwise might acquire too great momentum. For the same purpose, if required, I may in addition provide a friction-brake in the interior of the outer case or shell D.

I may construct the outer case or shell so that it only partially incloses the rotatable drum or cage, in which case no indicating

device would be required as the labels on the files could be seen by the operator as they were successively brought into view. The shape or configuration of the outer case or shell is not essential to my invention, all that is necessary being that it shall support the rotatable drum or cage. Sometimes I fit the rotatable drum in an ordinary cylinder writing-table, as shown in Fig. 6, when the outer case D, supporting the axle of the drum or cage, forms part of the writing-table. In this construction a wheel-segment drum or cage may be used.

Fig. 7 shows part of a modified form of pedestal writing-table wherein my drum file-cabinet is arranged to rotate on a vertical axis in two tiers rotating together or separately as desired.

A file case or cabinet such as is herein described may be used as an indicator in connection with a library, the radial compartments in the rotatable drum or cage having filed therein tabs or labels corresponding to the books or volumes on the shelves of the library, so that the case or cabinet will serve as an index to the books or volumes on the various shelves, &c., of the library.

What I claim is—

1. A file case or cabinet, consisting of a drum made with radial compartments to receive the files, and mounted in an outer case so as to be rotatable, a circular indicator having labels, corresponding to labels on the files and carried by the axle of the drum on the outside of the box, a ring fixed upon the box and concentric to the indicator, and having a slot, locking-plates pivoted at each indicating-character on the indicator and hinged thereto and adapted to be turned into and out of the slot, for the purpose hereinbefore described. 100

2. A holder for the collection of documents, consisting of a rotary cellular wheel A, having compartments radiating from the center, a plate K with a ring K^2 , divided into equal divisions, corresponding with the number of said compartments, and said plate having as many locking-plates H, pivoted in notches at its rim as there are compartments, the said locking-plates being rotary through an angle of ninety degrees, projections upon the locking-plates, and a ring J, having a single slot for receiving any one of the said projections and located against the said plate K, which latter is rigidly secured to the axle of the wheel A. 110
